LAND ANCHOR

George Kuhn, Takoma Park, Md.

Application March 17, 1930, Serial No. 436,575
Renewed October 17, 1933

7 Claims. (Cl. 189—91)

The present invention relates to an earth anchor and particularly to such an anchor of the screw type provided with helical blades which, when the anchor has been screwed into final position, may be radially projected relative to the shank of the anchor to lock the latter securely in the ground. Inasmuch as according to the present invention a relatively large projection of the blades is possible, these may be made of relatively small size so as to be easily turned in sinking the anchor and yet provide adequate resistance to dislodgment of the same.

According to the present invention, the blades may be projected, when the anchor has been sunk to the desired depth, by a further rotation of the shank in the unscrewing direction in the one instance, or by a further rotation in the entering direction in another instance. In the first instance, a tubular socket wrench may be utilized to prevent the projection of the blades upon reverse rotation of the shank so that if an obstruction is encountered the anchor may be removed and set in a new position. In the second instance, such a tubular wrench must be provided in order to prevent the projection of the blades as the anchor is being sunk. In this latter instance, after the blades have been projected, they may again be retracted upon reverse rotation of the shank so as to enable the anchor to be withdrawn from the ground.

The invention will be particularly described with reference to the accompanying drawings, wherein

Figure 1 is an elevation of the lower end of the anchor with the tubular socket wrench shown in section.

Figure 2 is a plan view of the lower end of the anchor with the shank in section.

Figure 3 is a view similar to Figure 2 showing the blades in projected position.

Figure 4 is a section on line 4—4 of Figure 3.

Figure 5 is an enlarged end view of the socket implement.

Figure 6 is an elevation of a second embodiment of the invention with the socket implement shown in section.

Figure 7 is a plan view of the second embodiment with the shank shown in cross section.

Figure 8 is a view similar to Figure 7 with the blades shown in projected position, and

Figure 9 is a section on line 9—9 of Figure 8.

Referring first to Figures 1 to 5, reference numeral 10 denotes an elongated rod or shank having at its lower end a radially expanded portion 11 terminating in a point 12. The extremity of portion 11 opposite point 12 forms an annular shoulder 13 whose face is in a plane substantially at right angles to the axis of the shank.

As shown in Figure 1, the main portion of the shank is cylindrical, but above its enlarged ex-

tremity it is squared off or reduced at its opposite sides and projecting from these sides in spaced relation to shoulder 13 are oppositely projecting shoulders 14 and 15, each of substantially the same radial projection as shoulder 13. 65 These shoulders 14 and 15 are provided with bores parallel to the axis of shank 10 and adapted to receive pivot pins in the form of cap screws 16 and 17, whose lower ends may be screw threaded in registering bores in shoulder 13. 70

As shown, in the drawings, two helical blades or wings 18 and 19 are provided, each having integral with its leading end and at its inner edge, a lug 20 or 21 extending a substantial distance around shank 10 and each having a portion in advance of the leading edge of its associated blade adapted to be engaged between shoulders 14 or 15 and 13 and having a bore adapted to receive a pin 16 or 17. Lug 20 has an extension 22 adapted to lie along rod 10 and lug 21 has a similar extension 23, these extensions defining, in the retracted position of the blades and in conjunction with shoulders 14 and 15, a crown adapted to be received in a socket element 24 fixed to the end of a tubular member 25. The opposite end of tubular element 25 is squared to receive a wrench as is also the upper extremity of rod 10. The lower portions of the lugs form a continuation of the cylinder defined by enlargement 11, and it will be seen that the portion of each lug engaged by the pivot pin is at substantially right angles to its main body portions. 90

It will be noted that the reduced portion of rod 10 immediately above shoulders 14 and 15 serves to permit the insertion of pivot pins 16 and 17 in their respective bores. As a matter of fact, these pivoting elements need not be in the form of cap screws but can be in the form of simple pins which may be dropped in their receiving apertures and seated against the bottom of the bores in expanded portion 11. 95

It will be obvious that the anchor as described may be screwed in position either by rotation to the right of rod 10 or tube 25. The tube will ordinarily be used since otherwise if an obstruction is encountered before the anchor has been fully sunk, it will be impossible to withdraw it by reverse rotation of rod 10, since such rotation causes the projection of the blades and consequent locking of the anchor. When the socket implement is used, however, it is obvious that it will prevent projection of the blades and the anchor may be unscrewed and set in a new position. 100

It will be understood that when the sunk rod is reversely rotated, the socket member having previously been withdrawn, the frictional engagement of the blades with the earth will restrain them from participation in the rod rotation and 105 110 115 120

they will be cammed into radially projected position and engaged in earth not disturbed during the entering operation. The resistance of the earth to the reverse rotation of the blades is greater than its resistance to their radial projection.

The embodiment according to Figures 6 to 9 is exactly the same as that described with reference to Figures 1 to 5, with the exception that 10 in this instance lugs 26 and 27, which have upward squared extensions 26' and 27', are fixed to the trailing ends of blades 28 and 29, and their pivoting portions are disposed to the rear of the trailing ends. According to each of the embodiments, the blades extend somewhat more than 15 half way about the shank, which means that the inner edges of the blades at their free ends must be cut away to permit their free pivotal movement. This being the case, the inner edges of 20 the leading ends of the blades, according to Figures 6 to 9, are somewhat spaced from enlargement 11, thus forming crevices likely to catch roots or the like and prevent rotation of the anchor. I accordingly form lugs 30 and 31 on 25 enlargement 11 as shown in Figures 7 and 9, these being so formed as to fill in the spaces which would otherwise exist so that the blades present a substantially continuous entering edge up to the enlargement.

30 According to this second embodiment, upon rotation of rod 10 in the entering direction, the same camming action is exerted on the blade as is exerted upon reverse rotation in the first embodiment, and consequently in sinking this 35 type of anchor, it is essential that the socket implement be engaged around extensions 26' and 27' to hold them against the shank. When the anchor has been sunk to the desired extent, the implement is withdrawn and upon rotating shank 40 10, still in the entering direction, the blades are expanded due to the resistance of the earth to their rotation. If it is desired to remove the anchor, shank 10 is turned in the unscrewing direction, whereupon the blades are first retracted to the position of Figures 6 and 7 and then move upwardly out of the ground. This 45 form of anchor is particularly useful in temporary installations.

50 It will be understood that I do not limit myself to the precise mechanical details shown and described, since many modifications are possible without departing from the invention as defined in the following claims.

I claim:

- 55 1. In a device of the class described, an elongated rod having a pointed lower end, a downwardly unobstructed helical blade extending part way around the rod adjacent the lower end of the latter, and pivoting means mounted on the 60 rod and engaging the blade, the axis of said pivoting means being parallel to the longitudinal axis of the rod, the blade being outwardly radially movable relative to the rod about said pivoting means.
- 65 2. In a device of the class described, an elongated rod having a radially expanded terminally pointed portion at one end thereof provided with a bore substantially parallel to the longitudinal axis of the bar, said portion being tapered from 70 its extreme outer periphery to its point, a helical

blade extending part way around the rod adjacent said expanded portion, and a pivot pin mounted in said bore and in engagement with said blade, the blade being outwardly radially movable relative to the rod about said pin.

80

3. In a device of the class described, an elongated rod having a radially expanded terminally pointed portion at one end thereof provided with a bore substantially parallel to the longitudinal axis of the rod, said portion being tapered from its extreme outer periphery to its point, a shoulder on said rod spaced from said expanded portion and having a bore in alignment with said first-mentioned bore, a helical blade partially surrounding the rod adjacent said expanded portion, a lug on said blade engaged between said expanded portion and said shoulder and provided with a bore aligned with those above mentioned, and a pin engaged in said bores, the blade being outwardly radially movable relative to the rod 95 about said pin.

90

4. In a device of the class described, a lower end portion tapered to a point at its lower extremity, a pair of pins secured to the upper end of said portion within the peripheral outline of said upper end and in parallel relation to the axis of said portion, and helical blades respectively pivoted adjacent their leading ends on said pins and radially projectable relative to the rod upon reverse rotation of the latter.

105

5. In a device of the class described, a lower end portion tapered to a point at its lower extremity, a pair of pins secured to the upper end of said portion within the peripheral outline of said upper end and in parallel relation to the axis of said portion, and helical blades respectively pivoted adjacent their trailing ends on said pins and radially projectable relative to the rod upon rotary movement of the latter in the entering direction.

110

6. In a device of the class described, a lower end portion tapered to a point at its lower extremity, a pair of pins secured to the upper end of said portion within the peripheral outline of said upper end and in parallel relation to the axis of said portion, lugs mounted on said pins and adapted to lie substantially within the peripheral outline of said upper end, and helical blades having their respective inner edges fixed to said lugs adjacent their leading ends, the blades 125 being projectable upon reverse rotation of said lower end portion, the lugs projecting upwardly to define a polygonal crown adapted to be engaged in a socket wrench.

115

7. In a device of the class described, a lower end portion tapered to a point at its lower extremity, a pair of pins secured to the upper end of said portion within the peripheral outline of said upper end and in parallel relation to the axis of said portion, lugs mounted on said pins 135 and adapted to lie substantially within the peripheral outline of said upper end, and helical blades having their respective inner edges fixed to said lugs adjacent their trailing ends, the blades being radially projectable upon rotary movement of said lower end portion in the entering direction, the lugs being upwardly extended to define a polygonal crown adapted to be engaged in a socket wrench.
